Primary Examiner — Patricia A Palasik(74) *Attorney, Agent, or Firm* — IDEA Intellectual Limited; Margaret A. Burke; Sam T. Yip(57) **CLAIM**

The ornamental design for a painting robot machine, as shown and described.

DESCRIPTION

FIG. 1 is a perspective view of a first embodiment of a painting robot machine;

FIG. 2 is a frontal view of the first embodiment of the painting robot machine;

FIG. 3 is a rear view of the first embodiment of the painting robot machine;

FIG. 4 is a right side view of the first embodiment of the painting robot machine;

FIG. 5 is a left side view of the first embodiment of the painting robot machine;

FIG. 6 is a top view of the first embodiment of the painting robot machine; and,

FIG. 7 is a bottom view of the first embodiment of the painting robot machine.

The broken lines in the drawings depict portions of the painting robot that form no part of the claimed design.
